UNITED STATES PATENT OFFICE

ROBERT EUGENE MILLER, OF BAINBRIDGE, GEORGIA, ASSIGNOR TO THE MILLER MANUFACTURING CO., OF BAINBRIDGE, GEORGIA

BOTTLE UNLOADER

Application filed August 16, 1926. Serial No. 129,503.

This invention relates to a bottle unloader. It more particularly relates to an automatic bottle unloader.

An object of the invention is to provide an apparatus for automatically taking bottles from the bottle chain cups of a bottle sterilizing or other machine and for placing them on a carrier chain or belt without the necessity of the bottles being touched by the operator's hands.

Another object is to provide an apparatus for automatically unloading bottles, which is easily operated and installed and which comprises relatively few parts.

Other objects and advantages will herein-after appear.

An embodiment of the invention is illustrated in the accompanying drawings; in which,

20 Figure 1 is a side elevation of the unloading apparatus.

Figure 2 is an end elevation looking toward the left hand end of Figure 1.

Figure 3 is an end elevation looking toward 25 the right hand end of Figure 1.

Figure 4 is a transverse vertical section taken on line 4—4 of Figure 5.

Figure 5 is a top, plan view of the apparatus.

30 In the different figures of the drawings, 1 indicates a row of tilting boxes, each having slidably mounted fingers 2, adapted to engage the neck of a bottle 4, as indicated in Figures 5 and 3. The bottles are brought to

35 the unloading apparatus, held with their necks down in cups 3, the cups being carried by a conveyor, from a washer or sterilizer, and moving in the direction of the arrow in Figure 5. The present invention is a machine

40 which takes the inverted bottles from the cups of the conveyor, rights them and places them on a second conveyor, traveling toward a filler, or other apparatus.

45 For this purpose, the row of boxes 1 tilts to the position in Figure 3, while traveling horizontally a short distance in step with the cup conveyor, the fingers slipping forward to embrace the necks of the bottles in the cups, then the row of boxes tilts to the position in 50 Figure 2, causing the bottles to topple out of

the fingers and be precipitated upright upon the chain members 31 of the second conveyor, Figure 2.

Boxes 1 are mounted on shaft 29, which may be squared except at its bearings, the shaft being rotated through a suitable angle by rocker 28, Figure 2, this being connected by link 27 to a crank 26 on the end of the main drive shaft 6. On the other end of shaft 6 is a gear 16, which may be connected to the driving mechanism of the cup conveyor. Shaft 6 also carries cams 18, 5, and 32, which perform the various operations in proper sequence, each revolution of shaft 6 completing one cycle of operation in step 60 with the cup conveyor, as described below.

As the boxes 1 tilt backward and are just reaching the position in Figure 3, the fingers 2 are projected to engage the necks of the inverted bottles in cups 3. Under each box, secured to the slidably fingers 2, is a lug 20. All the lugs are in a row and a bar 19 is in a position to be behind the row of lugs as the boxes tilt back and down. Bar 19 is supported on a pair of rockers 24, Figures 5, 70 3 and 4, carried on shaft 23, which is rotated through a suitable angle by rocker 24', Figure 4, being connected by link 21 to arm 22, Figure 1, which is mounted on shaft 8. Arm 22 has an upward extension 22', Figure 5, 75 80 which carries a roller 22'', bearing on cam 18.

As shaft 6 rotates, then, cam 18 causes bar 19 to engage the row of lugs 20 and project all the fingers 2 to engage the bottle necks, just as crank 26 brings boxes 1 to the position in 85 Figure 3.

But the bottles in the conveyor cups are traveling continuously along, so that the boxes and fingers must keep step for a short distance. For this purpose, shaft 29 which 90 carries the boxes is shiftable in its bearings and has a race member 15, Figure 1, 3 and 5, secured on its end remote from rocker 28 which gives it rotation. Engaging the race is a pin 14, Figures 1, 3 and 5, carried by a 95 rocker 12, this being mounted on shaft 13, Figure 1, which carries rocker 11. The latter is connected by rod 10 to rocker 7, which is pivoted midway of its length on shaft 8 and carries at its other end roller 9, bearing 100

on cam 5. By this train, the rotation of drive shaft 6, with its cams 5 and 18 and crank 26, shifts boxes 1 a short distance horizontally in step with the cup conveyor, while the boxes tilt back and the fingers engage the bottle necks.

Crank 26 and rocker 28 now tilt boxes 1 forward, lifting the bottle necks from the cups and causing the bottles to topple over out of the fingers and fall upright against guide 40, Figure 2. In this position of the boxes, fingers 2 and lugs 20 drop by gravity, ready to be projected again in the next backward tilting of the boxes. As indicated in Figure 2 and seen better in Figure 1, the boxes may be of two lengths, the longer boxes reaching to the second row of bottle cups of the cup conveyor, Figure 5, and the shorter boxes to the first row.

The bottles, in falling upright from the forward tilting boxes, do not fall immediately on conveyor chains 31, for the box sides would interfere with their traveling away. Until the boxes tilt backward out of the way, the bottles rest on a bar 30, Figures 2 and 5, indicated by dotted lines in Figure 1, which rises between chains 31, to hold the bottles out of contact with the chains, as in Figure 2. Bar 30 is supported on the horizontal members of a pair of bell cranks 36 and 37, Figure 1, being retained in position by pins 38, the vertical members of the bell cranks being connected together by rod 35, this being connected by link 34 to rocker 33 on shaft 8. Integral with rocker 33 is rocker 33', Figures 1 and 5, which carries roller 33", Figure 5, bearing on cam 32 on drive shaft 6. The rotation of shaft 6, then, causes bar 30 to rise above chains 31 to receive the bottles and to lower them upon the chains as the boxes tilt backward out of the way. This completes the cycle of operations, which is repeated in automatic sequence, each revolution of drive shaft 6, unloading a row of inverted bottles, righting them and sending them away on the second conveyor.

Guide 40 is mounted on spring hinges 41, Figure 2, so as to yield outwardly in case bottles get jammed. Further safety devices may be provided, such as constructing link 27, or 21, Figures 2 and 4, as a tube telescoped over a rod and held normally contracted by a spring, such as spring 39, or 21'.

The invention is not intended to be limited to the form or any of the details shown or described, but is intended to embrace the scope of the following claims.

What is claimed is:

- 60 1. A bottle unloader, comprising a tiltable box; fingers slidably mounted under the box, adapted to be projected to engage the neck of an inverted bottle; and means for tilting the box, to cause the bottle to topple out of the fingers and right itself in the tilting box.
- 65 2. A bottle unloader, comprising the structure of claim 1; guides for receiving the righted bottle from the tilting box; and a conveyor between the guides, adapted to transport the bottle away.

3. A bottle unloader, comprising the structure of claim 1; a conveyor adapted to transport the bottle away from the box; a release member, adapted to hold the bottle out of contact with the conveyor until the tilting box has receded, then to lower the bottle upon the conveyor; and cam means for performing these actions in sequence.

4. A bottle unloader, comprising a conveyor having cups for containing inverted bottles; a plurality of tiltable boxes in a row beside the conveyor; fingers slidably mounted under the boxes; means for projecting the fingers to engage the necks of bottles; means for tilting the boxes, to cause the bottles to topple out of the fingers and right themselves in the boxes; a second conveyor positioned to receive the row of righted bottles from the tilting boxes; and a bar adapted to hold the row of bottles out of contact with the conveyor until the boxes have receded, then to lower them upon the conveyor.

5. A bottle unloader, comprising the structure of claim 4; means for moving the row of boxes a limited distance in the same direction as the first conveyor, then back; and cam means, operatively connected with the first conveyor, for performing these actions in proper sequence and in step with the first conveyor.

6. A bottle unloader, comprising a row of boxes mounted on a rotatable and longitudinally shiftable shaft; pairs of fingers slidably mounted under the boxes, each pair having a depending lug; a bar mounted on rocker arms, adapted to engage the lugs and project the fingers; a race on the shiftable shaft; a rocker arm, having a pin in the race, adapted to shift the shaft and its row of boxes a limited distance to keep step with a carrier of bottles; a rocker arm on the shiftable shaft, adapted to rotate the shaft and its row of boxes; a conveyor adapted to receive bottles from the rotating boxes; a bar parallel with the conveyor; rocker arms supporting the bar, for causing the bar to lift the bottles out of contact with the conveyor; a drive shaft; and cams and cranks borne by the shaft, with connecting rods for actuating the rocker arms to perform the said actions in sequence.

In testimony whereof I affix my signature.
ROBERT EUGENE MILLER.
